WELL APPARATUS

Karl E. Young, Houston, Tex.

Application February 6, 1933, Serial No. 655,322

3 Claims. (Cl. 166—1)

This invention relates generally to deep wells and specifically to oil wells.

After a deep well has been drilled in certain formations, it is frequently desirable to utilize the energy of the natural gas in the recovery of the oil. The conventional method of doing this consists in lowering a pipe having a screen on the lower end thereof through the gas so that the screen is submerged in the oil. The oil entering the screen at a high velocity carries the sand with it and the sand closes the openings in the screen. Another objection to the conventional method is that the gas soon enters the upper openings in the screen and passes upwardly, leaving the oil behind. This results in the production of too much gas and too little oil.

This invention has for one of its objects the provision of a method and apparatus to prevent the foregoing.

20 The preferred embodiment of the invention includes means to reduce the velocity of the oil entering the outer screen, so that the sand will not close its openings; and means to prevent objectionable escape of the natural gas, so that its energy may be more efficiently utilized to effect the ejection of the oil.

The preferred embodiment also includes means whereby, when the pressure of the natural gas falls to a predetermined amount, gas under artificial pressure may be admitted to the well to eject the oil.

The apparatus is also constructed so that the screen may be quickly and easily cleaned without removing it from the well.

35 Other objects will hereinafter appear.

The preferred embodiments of the invention are illustrated by the accompanying drawing wherein Fig. 1 is a sectional elevation of one embodiment of the invention; Fig. 2 a fragmentary sectional elevation of another embodiment of the invention; and Fig. 3 a fragmentary sectional elevation of the third embodiment of the invention. In Fig. 1 the well casing is indicated at 1. It is anchored in the conventional manner as indicated at 1a. Within and extending downwardly from the lower end of the casing 1 is an outer pipe 2. Within the outer pipe 2 is an inner pipe 3 and within the inner pipe 3 is a tubing 4. The outer pipe has near its lower end a screen 5 and near the lower end of the inner pipe 3 is a screen 6. The screen 5 has a number of openings above the openings in the screen 6, and the lower end of the tubing 4 terminates below the openings in the screen 6. The lower ends of the pipes 2 and 3 are closed. The total effective area of the

openings in the screen 6 is less than the total effective area of the openings in the screen 5. The screen 6 may, if desired, be made of a finer mesh than the screen 5. Flow lines 7, 8, and 9 are connected to the tubing 4, the space between the tubing 4 and the inner pipe 3, and the space between the inner pipe 3 and the outer pipe 2, respectively. In the pipe 7 are valves 10 and 11; in the pipe 8 are valves 12 and 13; and in the pipe 9 are valves 14 and 15. The pipes 7, 8, and 9 are connected together and the connections include valves 16 and 17.

The total area of the openings in the screen 6 is less than the total area of the openings in the screen 5. This reduces the velocity of the oil 15 entering the screen 5 and the openings in the screen 5 are, therefore, not closed by sand.

The openings in the screen 6 are below the openings in the screen 5 and the apparatus is so positioned that the openings in the screen 6 are 20 below the level of the oil. Therefore, only a small quantity of the gas is permitted to escape, the energy of the gas being efficiently utilized to eject the oil through the tubing 4.

In normal operation the valves 15 and 13 are 25 closed and the valves 10 and 11 are open. Now if it is desired to clean the inner screen 6, the valve 11 may be closed, the valves 12 and 13 and 14 and 15 opened and gas under artificial pressure may then be forced downwardly into the space 30 between the tubing 4 and the inner pipe 3 outwardly through the screen 6 to clean said screen and thence upwardly in the space between the pipes 2 and 3 outwardly through the valves 14 and 15. 35

In Fig. 2 the casing is indicated at 18, the outer pipe at 19, the inner pipe at 20 and the tubing at 21. A packing 22 is placed between the inner pipe 20 and the screen 23 of the outer pipe and above the screen 24 of the inner pipe. This arrangement can be utilized after the pressure of the natural gas has diminished to a point where it is no longer effective. Gas under artificial pressure may then be pumped down through the valves 14 and 15 (Fig. 1) downwardly in the space 40 between the pipes 19 and 20 and outwardly through the upper openings of the screen 23 above the packing 22 into the upper portion of the sands. Upon entering the upper portion of the sands, this gas under artificial pressure will exert 45 a downward pressure on the oil therebelow, effecting the entrance of said oil through the openings of the screen 23 below, through the openings of the screen 24 and finally into the tubing 21, through which it will be conducted upwardly and 50

outwardly through the valves 10 and 11. This result could not be accomplished without the packing 22 because the gas would, in that event, merely force the oil back into the sands. If the 5 valves 14 and 15 were then closed, the gas would escape through the tubing 21, leaving the oil in the sands except for that portion of the oil which might be accidentally brought up with it.

It will be understood that any number of pipes 10 may be employed. For example, in Fig. 3 the casing is indicated at 25, the outer pipe at 26, the first inner pipe at 27, the second inner pipe at 28 and the tubing at 29. The screen 30 of the outer pipe has openings above the screen 31 of the first inner pipe, and the screen 31 of the first inner pipe has openings above the openings in the screen 32 of the second inner pipe. The opening in the tubing 29 is below the openings of the screen 32 of the second inner pipe.

20 Various advantages of this method and apparatus other than the above will be apparent to those skilled in the art.

It will also be understood that many embodiments of the invention other than the embodiments disclosed somewhat diagrammatically by the drawing herein will at once occur to those skilled in the art, all being within the scope of the following claims.

I claim:

30 1. Well apparatus including: an outer pipe having a screen; an inner pipe having a screen; the total area of the openings in said inner pipe screen being less than the total area of the openings in said outer pipe screen; some of the 35 openings in said outer pipe screen being above the openings in said inner pipe screen; a packing between said outer pipe screen and said inner pipe immediately above the openings in said

inner pipe screen and below some of the openings in said outer pipe screen; a tubing within said inner pipe and having an opening below some of the openings of said inner pipe screen; a valve between said tubing and the exterior of said well; a valve between the exterior of said well and the space between said tubing and said inner pipe; and a valve between the exterior of said well and the space between said inner pipe and said outer pipe.

2. Well apparatus including: an outer pipe having a screen; an inner pipe having a screen; the total area of the openings in said inner pipe screen being less than the total area of the openings in said outer pipe screen; some of the 15 openings in said outer pipe screen being above the openings in said inner pipe screen; a tubing within said inner pipe and having an opening below some of the openings of said inner pipe screen; a valve between said tubing and the exterior of said well; a valve between the exterior of said well and the space between said tubing and said inner pipe; and a valve between the exterior of said well and the space between said inner pipe and said outer pipe.

3. Well apparatus including: an outer pipe having a screen; an inner pipe having a screen; some of the openings in said outer pipe screen being above the openings in said inner pipe screen; a tubing within said inner pipe and having an opening below the openings of said inner pipe screen; a valve between said tubing and the exterior of said well; a valve between the exterior of said well and the space between said tubing and said inner pipe; and a valve between the exterior of said well and the space between said inner pipe and said outer pipe.

KARL E. YOUNG.
